PACKING CASE

Albert P. D. Belanger, Chicago, Ill., assignor of
one-half to Jacob Teller, Chicago, Ill.

Application August 17, 1942, Serial No. 455,021

9 Claims. (CL. 229—41)

This invention relates to packing cases of a type made of paper or other suitable sheet material, for use as a shipping crate or in any other capacity requiring a considerable degree of strength. It is one of the objects of the invention to provide a novel form and arrangement of parts by reason of which the case or crate may be assembled quickly and easily into sturdy box form without the use of rivets or other metal fasteners of any type. It is another object of the invention to provide an improved form and arrangement of holding means which can be very readily applied after the case has been filled and which will serve to hold the parts very strongly in box form so as to afford the required protection for the goods for shipment without danger that the box may collapse or be forced open. My improved arrangement comprises preferably a novel type of insert in the form of channels made of sheet material which hold the side and end panels of the box against inward movement, serve to divide the packing space into a plurality of compartments and effect a closure at the top of the case.

It is one of the objects of this invention to provide an improved form of parts by which added protection may be afforded to the contents of the box, this result being attained preferably by the provision of a tubular reinforcement extending across each end of the crate and preferably formed integrally with the end panel of the packing case.

It is another object of the invention to provide improved means for securing the side walls of the box to the cover plate structure so as to reinforce the construction and to hold the parts strongly and rigidly in position.

It is another object of the invention to provide improved means for effecting the final attachment of the parts together whereby a short length of cord may be utilized to advantage for securing the parts in their working position. Another object of the invention relates to an auxiliary securing means by which a short length of cord may be used for securing a portion of the contents of the crate together in unit form so as to expedite handling of the goods and to increase the strength of the completely bound crate.

It is another object of this invention to improve devices of this type in sundry details hereinafter pointed out. The preferred means by which the several objects have been attained are illustrated in the accompanying drawings, in which—

Fig. 1 is a central vertical sectional view through the preferred form of crate with a number of packages or bundles filling one-half of the crate, the thickness of the material from which the crate is made being emphasized for clearness of illustration;

Fig. 2 is a top plan view of the crate shown in Fig. 1;

Fig. 3 is a face view on a reduced scale of the blank from which the crate of Fig. 1 is formed;

Fig. 4 is a view similar to Fig. 3 but showing the side portions of the crate folded upwardly into position;

Fig. 5 is a face view of a band or strap by which the parts are secured in their closure position;

Fig. 6 is a top plan view of a crate like that shown in Figs. 1 and 2 but provided with a modified form of strap securing means;

Fig. 7 is a vertical sectional view corresponding to a portion of Fig. 1 but showing a modified arrangement of the parts;

Fig. 8 is a face view of a portion of the blank from which the structure of Fig. 7 is formed;

Fig. 9 is a perspective view of one end portion of a crate embodying my improvement but provided with a modified form of securing means for fastening the side of the crate to the cover plate structure;

Fig. 10 is an enlarged detail view showing the form of the lugs or hooks with which a fastening cord cooperates;

Fig. 11 is a view similar to Fig. 9 but showing a changed form of securing means adapted to cooperate with a fastening cord;

Fig. 12 is a perspective view of a crate like that of Fig. 1 but provided with a changed form of means for securing the parts in their final bound form; and

Fig. 13 is a perspective view of a modified form of insert employed for effecting an initial holding of the goods being packaged.

Referring now to Figs. 1 to 5 inclusive, in which corresponding parts are indicated by the same reference characters, 20 indicates a blank formed of tough heavy paper or other suitable sheet material and scored and cut so as to be adapted to be folded into box form. In Fig. 3, the lines of fold are indicated by dotted lines 50 serving to divide the blank for providing a bottom panel 21, side wall panels 22, end wall panels 23 and end tabs 24. With the blank in its flat condition as shown in Fig. 3, the end tabs 24 are first folded upwardly at right angles, after 55 which the side wall panels 22 are folded up as

shown in Fig. 4, serving to bring the end tabs 24 into face to face engagement with each other. The end wall panels 23 are then folded up outside of the end tabs 24, and end flaps 25 formed integrally on the upper edge portions of the end wall panels are turned downwardly inside of the end tabs 24, as is clearly shown in Fig. 1. As is best shown in Fig. 3, the end wall panels 23, the end flaps 25, and the end tabs 24 are all provided with openings 26 therethrough, such openings being preferably in the form of slots, and the arrangement being such that the slots are brought into position to register with each other when the parts are folded into the position as shown in Fig. 1.

With the parts in this condition, a plurality of inserts 27 are placed in position in the case. Each of the inserts as shown is in the form of a channel made of sheet material comprising an intermediate web portion and two side portions. In the arrangement illustrated in Fig. 1, two of the channels 27 are inserted in a row with the channels opening upwardly, and two additional channels 27 are placed in position with the channels opening downwardly. The arrangement is such that the inserts limit the inward movement of the end wall panels and the end flaps, particularly when the upwardly open channels have been filled with packages 28 or other goods as shown at the right end portion in Fig. 1. The inserts serve to divide the packing space in the case into compartments, and also serve as top closure means for the case.

For holding the parts securely together in their operative relationship, for shipment or storage, I thread a flexible strap 29 through the slots 26 and over the intermediate inserts 27. As is clearly shown in Fig. 5, the flexible strap 29 is provided at one end with a small loop 30 into which a pin 31 is insertable as shown in Fig. 2 for preventing withdrawal of the strap 29 toward the left in said Fig. 2. At its opposite end portion, the strap is provided with a plurality of loops 32 into any one of which a pin 33 may be inserted for holding the strap 29 tightened in position so as to prevent outward movement of the end wall panels 23 and end tabs 24. In the arrangement shown, the strap 29 is provided with tapered end portions 34 having openings therethrough for a ready attachment of a shipping tag if desired.

As is clearly shown in Fig. 2, strips 35 of gummed tape are preferably provided across the top faces of the inserts 27 with their end portions turned downwardly and secured to the outer faces of the side wall panels 22 for assisting in holding the parts in condition for shipment.

By the use of my improved construction, I am enabled to fold a packing case into condition for receiving packages therein very quickly and easily without the use of any attachments such as rivets or the like. In the final form of packing box, the construction is very rigid so as to afford ample protection to the goods. The arrangement is such that the structure can be provided very cheaply and readily, the structure comprising principally a blank cut and shaped complete by a stamping operation.

In the arrangement shown in Fig. 6, the construction is the same as that above described, except that a modified form of securing means is provided for insertion through the slots 26. In the arrangement shown in Fig. 6, two flexible straps 36 and 37 are employed in lieu of the single strap 29 as first described. Each of the

straps 36 and 37 is provided with a loop 38 at its outer end for receiving a pin 39 so as to engage with the outer face of the end structure of the case. At the inner ends of the straps 36 and 37, loops 40 are provided adapted to receive pins 41 which extend transversely beyond the side edges of the straps so as to enable the operator quickly and easily to wind a cord 42 about the pins for holding the straps 36 and 37 securely tightened in position. The arrangement is such that a short length of cord 42 will suffice and such that the connection of the parts can be effected very easily and quickly.

In the arrangement shown in Figs. 7 and 8, the construction is the same as that shown in Figs. 1 to 5 except that the flap 25 has been eliminated from the upper edge of the end wall panel 23. Instead of such flap 25, the end wall panel 23 is provided with a tubular reinforcement part 43 which is formed integrally with the end wall panel. As is clearly shown in Fig. 8, the sheet material is scored at a plurality of points for permitting the sheet to be folded into the desired tubular form, in which it is secured preferably by means of an adhesive.

In Fig. 9, I have shown a modified form of auxiliary securing means employed in lieu of the gummed strips 35. This arrangement comprises the provision of a series of lugs 44 in the form of hooks formed from the sheet material by a cutting and pressing operation during the formation of the blank, such lugs or hooks being formed on the upper edge portions of the side wall panels 22 and the side edges of the inserts 27. When the downwardly open channels 27 have been placed in position after the packing of the case, an operator is enabled very quickly and easily to bind the inserts 27 with the side wall panels 22 by means of a cord 45 at each corner 40 of the box, such cord being looped over the hooks or lugs and tied tightly in position.

In Fig. 11, I have shown an alternative arrangement for securing a tying cord 46 in position. In the arrangement in Fig. 11, stitches 47 are provided along the edges of the side wall panels 22 and the inserts 27 so as to enable the cord 46 to be threaded quickly into position and tightened for holding the parts in position.

Another modified arrangement is shown in Fig. 12 for enabling me to dispense with the flexible strap 29 or its equivalent. In the box of Fig. 12, the arrangement is the same as that above described except for the changed securing means. In the arrangement of Fig. 12, the end wall panels 23 are provided with elongated straps 48 which are provided with hooks or lugs 49 similar to the hooks 44 above mentioned, the arrangement being such that a cord 50 can be quickly and easily looped into position for securing the flaps 48 tightly together so as to hold the parts in the desired closed box form.

In Fig. 13, I have shown a modified form of insert. The arrangement shown is in the form of an upwardly open channel for use in lieu of one of the upwardly open channels 27 of the arrangement shown in Fig. 1. In the changed construction shown in Fig. 13, the upwardly directed wall portions at opposite sides of the channel are provided with flaps 51 upon which lugs or hooks 52 are provided for cooperation with a binding cord 53 by which the insert can be tightened about its contents.

While I prefer to employ the form and arrangement of parts as shown in the drawings, the invention is not to be limited to such ar-

angement except so far as the claims may be so limited, it being understood that changes might well be made in the construction without departing from the spirit of the invention.

I claim:

1. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, said end wall panels and said end tabs being provided with slots therein in position to register with each other when the parts are folded up into box form, a flexible strap adapted to be threaded through said slots, means at one end portion of said strap for limiting the movement of the strap through said slots, and a pin having releasable connection with the opposite end portion of said strap in adjustable position therealong adapted by engagement with the outer face of the end wall panel to prevent withdrawal of the strap from said slots and adapted thus to hold said end wall panels and said end tabs against movement outwardly and to hold the parts securely in box form.

2. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, means comprising a plurality of inserts in the form of channel members dividing the packing space into a plurality of compartments and serving to close the upper face of the packing case and to hold the ends and sides of the packing case against movement inwardly beyond their normal position, said end wall panels and said end tabs being provided with slots therein in position to register with each other when the parts are folded up into box form, a flexible strap adapted to be threaded through said slots and over said inserts, means at one end portion of said strap for limiting the movement of the strap through said slots, and a pin having releasable connection with the opposite end portion of said strap in adjustable position therealong adapted by engagement with the outer face of the end wall panel to prevent withdrawal of the strap from said slots and adapted thus to hold said end wall panels and said end tabs against movement outwardly and to hold the insert members against movement upwardly and serving thus to hold the parts securely in closed box form.

3. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely inside of said end wall

panels when the sides and ends are folded up, flaps formed integrally with said end wall panels so as to be adapted to be folded downwardly inside of said end tabs, means comprising a plurality of inserts in the form of channel members dividing the packing space into a plurality of compartments and serving to close the upper face of the packing case and to hold the ends and sides of the packing case against movement inwardly beyond their normal position, said end wall panels and said end tabs and said flaps being provided with slots therein in position to register with each other when the parts are folded up into box form, a flexible strap adapted to be threaded through said slots and over said inserts, means at one end portion of the strap for limiting the movement of the strap through said slots, and a pin having releasable connection with the opposite end portion of said strap in adjustable position therealong adapted by engagement with the outer face of the end wall panel to prevent withdrawal of the strap from said slots and adapted thus to hold said end wall panels and said end tabs and said flaps against movement outwardly and to hold the insert members against movement upwardly and serving thus to hold the parts securely in closed box form.

4. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, a plurality of inserts in the form of upwardly open channels arranged in a row in said case, a plurality of inserts in the form of downwardly open channels arranged about the first-mentioned channels respectively so as to provide a plurality of separated and closed compartments and so as to close the top face of the case, said two sets of inserts being arranged so as to hold the ends and sides of the packing case against movement inwardly beyond their normal positions, said end wall panels and said tabs being provided with openings therethrough in position to register with each other when the parts are folded up into box form, a flexible member adapted to be threaded through said openings and over said inserts, and means adapted by releasable engagement with said flexible member when threaded into position to hold said end wall panels and said end tabs against movement outwardly and to hold the insert members against movement upwardly and serving thus to hold the parts in closed box form.

5. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, tubular reinforcing parts formed on the outer faces of said end wall panels at their upper edges, said end wall panels and said end tabs being provided

with openings therethrough in position to register with each other when the parts are folded up into box form, a flexible member adapted to be threaded through said openings, and means adapted by releasable engagement with said flexible member to secure said member against withdrawal from said openings so as to hold the end panels and the end tabs against outward movement and thus to hold the parts securely in box form.

6. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, said end wall panels and said end tabs being provided with openings therethrough in position to register with each other when the parts are folded into box form, top panel means of sheet material for closing the upper face of the case when the case has been packed, hooks arranged on said top panel means and said side wall panels so as to hold a cord in position for binding the top panel means securely in closure position, a flexible member adapted to be threaded through said openings at the ends of the case and over said top panel means, and means adapted by releasable engagement with said flexible member to secure said member against withdrawal from said openings so as to hold the end panels and the end tabs against outward movement and to hold the top panel means against upward movement and thus to hold the parts securely in closed box form.

7. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, said end wall panels and said end tabs being provided with openings therethrough in position to register with each other when the parts are folded into box form, top panel means of sheet material for closing the upper face of the case when the case has been packed, hooks formed by cutting out lug portions from the sheet material of the side wall panels and the top panel means and adapted to hold a cord in position for binding the top panel means securely in closure position, a flexible member adapted to be threaded through said openings at the ends of the case and over said top panel means, and means adapted by releasable engagement with said flexible member to secure said member against withdrawal from said openings so as to hold the end wall panels and the end

tabs against outward movement and to hold the top panel means against upward movement and thus to hold the parts securely in closed box form.

8. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely next to the end wall panels when the ends and sides are folded up, means comprising a plurality of inserts adapted to be received downwardly into the case so as to close the upper face of the case, said end wall panels and said end tabs being provided with slots therein in position to register with each other when the parts are folded up into box form, a flexible strap adapted to be threaded through said slots and over said inserts, means at one end portion of said strap for limiting the movement of the strap through said slots, and a pin having releasable connection with the opposite end portion of said strap in adjustable position therealong adapted by engagement with the outer face of the end wall panel to prevent withdrawal of the strap from said slots and adapted thus to hold said end wall panels and said end tabs against movement outwardly and to hold the insert members against movement upwardly and serving thus to hold the parts securely in closed box form.

9. A packing case made from a piece of flexible sheet material scored to provide the several parts, comprising in combination a bottom panel of the sheet material, side wall panels formed integrally with the bottom panel at opposite sides thereof, end wall panels formed integrally with the bottom panel at opposite ends thereof, end tabs formed integrally with the side wall panels at opposite ends thereof so as to be adapted to be folded in transversely inside of said end wall panels when the sides and ends are folded up, flaps formed integrally with said end wall panels so as to be adapted to be folded downwardly inside of said end tabs, means comprising a plurality of inserts adapted to be received downwardly into the case so as to close the upper face of the case, said end wall panels and said end tabs and said flaps being provided with slots therein in position to register with each other when the parts are folded up into box form, a flexible strap adapted to be threaded through said slots and over said inserts, means at one end portion of the strap for limiting the movement of the strap through said slots, and a pin having releasable connection with the opposite end portion of said strap in adjustable position therealong adapted by engagement with the outer face of the end wall panel to prevent withdrawal of the strap from said slots and adapted thus to hold said end wall panels and said end tabs and said flaps against movement outwardly and to hold the insert members against movement upwardly and serving thus to hold the parts securely in closed box form.

ALBERT P. D. BELANGER.
